DETERGENT SOAP PRODUCT AND
PROCESS

Victor Mills, Ivorydale, Ohio, assignor to The
Procter and Gamble Company, Ivorydale,
Ohio, a corporation of Ohio

Application January 28, 1941, Serial No. 376,399

20 Claims. (Cl. 252—368)

This invention relates to improved detergent soap products and to methods of making the same.

The principal object of my invention is to provide by a relatively simple, economical, and continuous process a solid extruded soap containing a substantial proportion of soap in the readily soluble "beta" phase, and exhibiting a combination of other desirable characteristics not found in other soaps of similar phase composition. An especial object is to produce soap having a high sudsing rate, in all cases higher than the sudsing rate of ordinary framed soap of identical chemical composition, a quality which makes my new soap especially suited for use in hard water or in cold water.

A feature of the invention is that an aerated soap may be treated, without essential alteration of the steps of the process, in such a manner that it will be given an improved sudsing quality, thus producing a floating soap having all the desirable characteristics of my product.

Milled soaps, produced by working solidified but still slightly plastic flakes of reduced moisture content between several successive sets of steel or granite rollers and then compacting the particles in a plodder which extrudes the soap in solid bar form, usually contain (depending upon chemical composition and completeness of milling) a high proportion of a solid soap phase which has been identified as the "beta" soap phase. Framed soaps produced by allowing kettle soap to cool slowly to a solid state may also contain soap in the beta phase but usually in relatively smaller proportion. As will be noted hereinafter, beta soap phase is distinguishable by X-ray analysis. Similarly distinguishable is a less readily soluble solid soap phase, referred to as "omega" soap, which is formed when soap is rapidly cooled from a molten to a solid state without mechanical working. Of two soap bars of the same chemical composition, moisture content, and general granular structure, that bar which contains the greater ratio of beta phase soap to omega phase soap will develop suds the more rapidly when rubbed during use.

The crux of my invention is the discovery that mechanically agitating or working soap while it is being cooled from a fluid state through various degrees of plasticity causes the formation of beta soap when, and only when, the final temperature of the soap extruding from the agitating operation is reduced below a critical value which varies with the chemical composition of the real soap portion of the mass and with the moisture con-

tent; also, that when the temperature of the soap extruding from this cooling operation is kept above a lower limit at which the mass substantially loses its pasty cohesiveness, a product is formed which is softer and less tough and translucent than milled soap of like formula.

The critical temperature below which beta soap may be formed by mechanical agitation is in all cases low enough to permit extruding the soap in a form-retaining condition, yet high enough to permit extruding the soap at relatively low pressure in a condition of pasty cohesiveness such that air in finely divided bubble form may be retained when a floating soap is desired. I determine the critical extrusion temperature by noting the value at which the characteristic beta ring appears in X-ray photographs of soap samples representing different extrusion temperatures. A more readily available means of approximating the critical extrusion temperature is to compare sudsing rates of soap samples representing different extrusion temperatures with the sudsing rate of a sample of kettle soap of the same chemical composition slowly cooled from a fluid to a solid state as in commercial framing practice. The lower temperature limit of my process is readily recognized, when the extrusion temperature is gradually lowered, as that point below which an aerated soap of any given formula begins to become crumbly and non-cohesive.

One form of apparatus suitable for the practice of the invention, as well as representations of a photographic method of testing the product, is shown in the accompanying drawings, in which

35 Figure 1 is a diagrammatic showing of a preferred form of apparatus for use in the practice of the instant process, including the steps of reducing the moisture content of ordinary kettle soap while still in a molten condition and then cooling and agitating the same;

Figure 2 is a longitudinal sectional view of the cooling and agitating device shown in Figure 1;

Figure 3 shows a transverse section, taken substantially on the line 3—3 of Figure 2;

Figure 4 is a transverse sectional view on the line 4—4 of Figure 2; and

Figures 5, 6, and 7 are representations of photographs of X-ray diffraction patterns of soap in different phases.

50 In order to facilitate an understanding of the invention and of one method whereby the invention may be practiced, apparatus which may be employed for the purpose is illustrated in the drawings, and specific language is used to describe the same. It will nevertheless be under-

stood that no limitation of the scope of the invention is thereby intended, the practice of the invention with other forms of apparatus, capable of accomplishing the desired purpose, being contemplated.

Figure 1 shows diagrammatically the various component parts of an apparatus which may be so operated and controlled as to produce the soap of the present invention. A tank 11 is provided for the storage of molten soap, the lower portion of this tank communicating through a conduit 12 and a heater 14 with a spray nozzle 16 in a flash chamber 15, a pump 13 being associated with the conduit 12 to ensure continuous and uniform flow of soap to the flash chamber. The heater 14 may be supplied with high-pressure steam or other suitable heating medium, and may conform in structure to any known type of heat exchange device for raising the temperature of liquids. The flash chamber is provided at its upper end with a vapor pipe 17 for the escape of volatilized moisture through a condenser 18, cold water or other condensing medium being supplied to the latter to effect condensation of the discharging vapor.

Following the reduction of moisture content of the soap in flash chamber 15, the molten soap is conveyed through a conduit 19 by a pump 20 to and through a continuous crutcher 46, thence to a cooling device indicated generally at 24. Perfume may be introduced through pipe 47 and thoroughly mixed with the stream of hot soap passing through crutcher 46. Similarly, compressed air or other compatible gas may be introduced, if desired, at this point through a conduit 21 provided with a control valve 22, and distributed throughout the soap. The cooling device 24 is provided with an outlet orifice 25, through which the soap, cooled and otherwise treated as hereinafter described more fully, is extruded in the form of a continuous bar onto a traveling conveyor belt 26. The continuous soap bar may be severed into individual bars or lengths by a cutter, represented schematically at 21, which is disposed above the conveyor 26 and driven in timed relation therewith. In place of this bar cutter any other suitable means for converting the continuous extruded bar into individual bars, for example a bar molding device, may be employed.

The continuous crutcher indicated generally at 46, which forms no part of my invention, may be any suitable ingredient proportioning and mixing means such as the devices described in Robert V. Burt's Patents 2,024,425 and 2,203,980. It will be understood that any other means of supplying an aerated molten soap to the cooling device will serve my purpose. Also, while one of the advantages of my process is that it is quick and continuous, the soap may nevertheless be prepared as a batch, either aerated or un-aerated, for passage through the cooler and extruder.

Turning now to Figures 2, 3, and 4, constituting sectional views of the cooling device 24, it will be noted that the soap is delivered through conduit 19 into an annular chamber 28 defined by a generally cylindrical drum 29 and a shaft 33, the latter being supported for rotation on the axis of the drum. The drum 29 is formed of heat conducting material, such as metal, and is surrounded by a second cylindrical wall 31 to provide a cooling jacket, a cooling medium being introduced into the annular space 30 surrounding

the drum 29 through an inlet port 38, and being withdrawn therefrom through an outlet port 39.

As is apparent from the drawings, the soap is forced to flow through the chamber 28 in a relatively thin annular layer; excellent results have been obtained in practice by the employment of a shaft 33 and a drum 29 of such dimensions that the thickness of this layer is of the order of one inch or less. A plurality of scrapers 34, arranged as shown in Figure 3 at intervals about the shaft 33, are secured to the latter and positioned to engage and scrape the inner surface of the drum 29.

Communicating with the rear end of the drum 29, and preferably affording a continuation thereof, is a generally cylindrical drum 42.

Rigidly mounted within the drum 42 are a plurality of annular elements 32, each of which is provided with a plurality of substantially radial, inwardly directed arms 36, serving as baffles. A shaft 43, forming a reduced extension of the shaft 33, is threaded or otherwise secured to the rear end of the latter and is provided with a plurality of generally radial arms 35, disposed in proximity to the baffle arms 36 and cooperating therewith to agitate the soap. From the drum 42, the soap passes through a tapered discharge housing 44 and is extruded from the orifice 25 at the rear thereof. A motor 45 or other suitable driving means may be employed to rotate the shafts 33 and 43, as shown in Figure 1.

The details of the cooling and agitating device disclosed herein form per se no part of the present invention. Devices of this character are disclosed, for example, in the patent to Vogt, No. 1,783,864, dated December 2, 1930, and its Reissue No. 21,406, dated March 19, 1940, and are merely representative of apparatus which are found specifically suitable in the practice of the instant invention.

The operation of the apparatus illustrated herein in carrying out my process will be understood from the following descriptive example.

Sodium soap, in the neat phase, prepared from a mixture of 20 per cent coconut oil and 80 per cent tallow by the usual well known kettle process, and containing about 30 per cent of moisture, is stored in tank 11, Figure 1. It is heated to about 390° F., under a gauge pressure of 250 pounds per square inch or more to prevent volatilization of moisture, by pumping through a closed type of heater 14, heated by high pressure steam or other suitable medium. The soap is then discharged through spray nozzle 16 into chamber 15, where it flashes to atmospheric pressure with volatilization of sufficient moisture to reduce its moisture content to about 20 per cent; at the same time its temperature is reduced to that corresponding to the boiling point of soap containing this reduced percentage of moisture, or about 223° F.

By suitable adjustment of the conditions of soap temperature before flashing, pressure in the flash chamber, etc., soap of any desired moisture content below that of kettle soap may be obtained while still maintaining the soap in sufficiently fluid condition to permit pumping.

This hot molten soap of about twenty per cent moisture content, still in the neat phase, is then transferred by pump or other suitable means into and through the rest of the apparatus under sufficient pressure to accomplish this transfer at the rate desired. I have found that a pressure of between about ten and about twenty pounds per

square inch, measured near the pump outlet, is usually sufficient depending on the size of the extrusion orifice and other variables. In the cooling device, while in a thin layer not substantially greater than one inch, the soap is cooled to an average temperature of about 140° F., at which temperature it has a pasty cohesiveness (apparently due to the presence of some unsolidified soap in the mass), but will retain its shape upon extrusion (due to the presence of a substantial proportion of soap in solid phase). Simultaneously air is introduced into the molten soap stream through valve 22, at a controlled rate proportionate to the rate of flow of soap, and in amount sufficient to reduce the specific gravity of the soap when it reaches cutter 27 to about 0.80. The film of soap which is chilled on the inner surface of the cooling jacket is quickly scraped off by the scrapers 24 and mixed with uncooled soap, with agitation. In the apparatus described, I find a cooling medium consisting of water between 35° F. and 65° F. to be satisfactory depending on rate of water flow and finished product properties desired, but cold brine or liquid ammonia or other cooling medium may be used instead. The soap then passes through drum 42, where it is further mixed by the rotating arms or paddles 35 and by passing between the stationary baffle arms 36 without additional chilling. It is then extruded as a form-retaining mass into the atmosphere or into a low pressure zone through orifice 25 which has the required shape to produce a continuous blank bar of desired form. This continuous bar is cut into short individual bars of the desired length, and these bars are cooled without undue delay to a temperature convenient for the usual final bar stamping or pressing operation, which may suitably be performed when the temperature of the soap is about 100° F. The process is continuous, beginning with soap in storage tank 11 up to the bars made by the apparatus described.

Further description of my process and product will be facilitated if consideration is given at this point to important changes that are brought about in soap subjected to my process.

The beta and omega phases, although of identical chemical composition, differ fundamentally in crystalline structure as well as in their different solution and sudsing rates already referred to. The X-ray diffraction patterns exhibited by these two phases are quite different and serve to identify them, as illustrated in Figures 5 and 6 for sodium soap made from 20 per cent coconut oil and 80 per cent tallow. For purposes of identification the presence of the diffraction ring corresponding to an interplanar distance in the crystal of approximately 2.95 Å. as shown in Figure 6 is ordinarily sufficient to prove the presence of the omega phase, while the presence of the ring corresponding to an interplanar distance of approximately 2.75 Å. as shown in Figure 5 is ordinarily sufficient to indicate the presence of the beta phase. The interplanar distances of course vary somewhat, although usually only slightly, with some variations in the composition of the soap, but the spacings given by way of example, coupled with the diagrams Nos. 5 and 6 illustrating the relative intensities of lines and other spacings as well, will serve to denote the characteristic X-ray patterns of the two phases.

Figure 7 is a representation of a photograph of the X-ray diffraction pattern exhibited by soap containing both beta phase soap and omega phase

5 soap in substantial amounts. The relative intensities of the 2.95 Å. and 2.75 Å. rings, and of other characteristic rings, provide a means of estimating the relative amounts of these two phases in a sample of soap. Thus the proportion of one of these phases in one soap in relation to the proportion of the same phase in another soap of like chemical composition can readily be estimated by comparison of the intensities of the characteristic ring for that phase in X-ray diffraction photographs of the two soaps taken under comparable conditions.

10 The X-ray diffraction patterns illustrated in the figures were obtained by passing a beam of X-rays from a copper target through two separated pin holes to eliminate all but substantially parallel rays, passing these rays unfiltered through a one millimeter layer of the soap sample, and recording the resulting radiations on a flat photographic plate located five centimeters beyond the sample, the general technique being that described in George L. Clark's "Applied X-rays," third (1940) edition, chapter XIII. The diameters of the 2.95 Å. and 2.75 Å. rings on the photographic negatives obtained in this manner were 5.85 centimeters and 6.40 centimeters respectively.

15 When the 2.75 Å. ring is just barely visible on the photograph, after an exposure of 100 minutes with X-rays emanating from a vacuum tube operated at 40 kilo volts (peak on rectified current) and 25 milliamperes and passing through pin holes having diameters of about 0.025 inch, the soap through which the rays were passed contains a substantial amount of soap in the beta phase. Soap made by my process which exhibits the 2.75 Å. ring even faintly is found to have a higher sudsing rate than soaps of the same composition (as regards real soap molecular composition, builder formula, and moisture content) which do not exhibit this ring and which have been made by other processes or by a process similar to mine but above the critical temperature of my process.

20 45 The following table shows the comparative sudsing rate: (1) of ordinary framed kettle soap, unaerated, (2) of the same soap dried to 20 per cent moisture before framing, (3) of soap containing 20 per cent moisture made by my new process, (extruded at 140° F.), with the air injection step omitted, (4) the same as 3 but extruded at 204° F. into a small container (because at this temperature it is not form-retaining) and cooled more rapidly than framed soap, and (5) of ordinary milled soap containing 14 per cent moisture. All of these soaps were soda soaps, made from the same fat formula, namely, 20 per cent coconut oil and 80 per cent tallow. Differences in sudsing rates are measured by determining the number of rubs with a sponge required to produce a stable suds in a gallon of 85° F. water of 7 grains of calcium carbonate hardness per gallon with a bar of a given size and tested under standardized conditions. The 50 number of rubs required for each of these soaps in this test is due solely to the physical condition of the soap. The higher sudsing rates are obviously characterized by the smaller number of rubs required in the test. Comparison of column 2 with column 1 shows that mere reduction of moisture of framed soap does not increase the sudsing rate but rather tends to reduce it. A comparison of columns 3 and 5 with columns 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

framed soaps. Column 4 shows that the desired high sudsing rate is not obtained when the extrusion temperature in my process is too high.

	1 Ordinary framed soap	2 Same as (1), but dried before framing	3 New process soap	4 Same as (3), but extruded at 204° F.	5 Ordinary milled soap
Moisture content percent	30	20	20	20	14
Number of rubs to produce stable suds	70	95	48	97	47

When soap at a temperature below its true critical temperature is agitated in such a manner that the particles of the mass are moved with respect to one another, soap which is present in the omega phase is transformed into the beta phase and the sudsing rate of the soap is increased. The extent of this transformation depends upon factors hereinafter mentioned.

Extrusion temperature	Depth of color	Opacity	Firmness	Break
Well above critical extrusion temperature.	Dark.....	Translucent.....	Semi-fluid. Not form-retaining.	Viscous fluid.
Slightly above critical extrusion temperature.	Very dark.....	do.....	Very firm. Not fully plastic.	Like "art gum" eraser.
At critical extrusion temperature.	Changing to distinctly lighter.	Changing to opaque.	Somewhat firm but pliable.	Breaks by own weight.
Slightly below critical extrusion temperature.	Very light.....	Opaque.....	Very soft and very pliable.	Stretches slightly before breaking.

The above mentioned true critical temperature may be considered as the highest temperature for a given soap at which the amount of beta soap that may be produced therein by thorough agitation, followed by prompt cooling to room temperature to stabilize the phase composition resulting from this agitation, is just enough to cause a sample of the soap to exhibit the characteristic 2.75 Å. ring when the aforementioned X-ray diffraction technique is employed. Insofar as I have been able to determine, agitation of the soap when above its critical temperature has no effect on the formation of beta soap; whereas when soap is thoroughly agitated below its critical temperature, and then maintained at a stable temperature without further agitation, the resulting amount of beta phase tends to be above the minimum amount required just to exhibit the 2.75 Å. ring.

The critical temperature is not the same for all soaps; it varies with changes in the "real soap formula" (by which term I mean the composition of the true soap portion of the product) and also with changes in the moisture content. For sodium soaps prepared by reducing the moisture content of kettle soap to 26 per cent, for example, the true critical temperature is found, by thoroughly agitating soap under controlled temperature conditions, to be about 160° F. when the real soap formula is composed of 20 per cent coconut oil soaps and 80 per cent tallow soaps, and it is about 150° F. when the real soap formula is composed of 50 per cent coconut oil soaps and 50 per cent tallow soaps. For the latter real soap formula the critical temperature is about 160° F. when the moisture content is 21 per cent. These critical values vary somewhat with changes in the characteristics of the fats employed. In general, for soap of a given "real soap formula" the critical temperature increases as the moisture content decreases.

In operating the apparatus illustrated, the

temperature of the extruding soap measured just after it leaves the orifice, which I refer to as the extrusion temperature, is a convenient guide in controlling the process. I have found in experiments with several typical soap formulas that the critical extrusion temperature for phase transformation is about 5° higher than the true critical temperature independently determined under controlled conditions. This seems reasonable from theoretical considerations inasmuch as the extrusion temperature is undoubtedly an average temperature resulting from mixing well chilled and transformed soap with less chilled soap. The critical extrusion temperature, which may be determined for soap of any formula as hereinbefore described, may also be judged by the appearance, feel, and break of the extruding soap. The following table, for example, indicates typical changes in easily noticeable physical characteristics exhibited by the extruding soap when producing non-aerated toilet soap of 15 to 27 per cent moisture content, when the extrusion temperature is varied:

35 Soap in the beta phase is not stable at high temperatures; under such conditions beta phase soap tends to revert spontaneously to the omega phase, or to a non-solid phase, and at the same time the sudsing rate of the soap, when brought back to its original temperature, decreases. Some of the beta phase soap in soaps of the aforementioned real soap formulas, containing about 20 per cent moisture and made by my new process, slowly reverts to omega phase (or reverts to a non-solid phase, and resolidifies as omega phase) at temperatures above about 160° F., and reverts more rapidly as the temperature is increased. Soaps of higher moisture content revert somewhat even below 160° F. If heated to temperatures above 200° F. the reversion rate of 40 50 55 60 65 70 75 80 85 90 95 100 105 110 115 120 125 130 135 140 145 150 155 160 165 170 175 180 185 190 195 200 205 210 215 220 225 of soap per hour and transform about the same proportion of the soap to the beta or more rapidly soluble phase as the proportion of beta phase soap found in ordinary milled soap of the same real soap formula, when soap of about 20 per cent moisture content, and having a real soap formula consisting of about 20 per cent sodium soaps of coconut oil fatty acids and about 80 per cent sodium soaps of tallow fatty acids, is supplied to the cooling device at a temperature of about 220° F. and is extruded therefrom at a temperature of about 140° F. Under these conditions agitation for as short a period as one minute or even less is effective in producing a suitable amount of transformation to the beta phase.

The lower extrusion temperature limit of my process, which as heretofore mentioned is that point below which the extruding soap substantially loses its pasty cohesiveness, apparently due to the solidification of the last remaining non-solid soap in the mass, is found to be about 125° F. when treating substantially unbuilt soap of the aforementioned real soap formula having any moisture content between about 14 per cent and 27 per cent. It is somewhat higher for soaps of lower moisture content and is somewhat lower for unbuilt soap of higher moisture content. I use the term "pasty cohesiveness" to describe that property of soap, at the point of extrusion within my operating range, which enables freshly separated masses of said soap to become reunited when brought together without requiring the application of high pressures such as are employed in plodding milled soap. The extruding soap mass, within the limits of my process, may be considered as a thick pasty magma consisting of a mixture of solid soap crystals in a viscous matrix of unsolidified soap.

Changes in the extrusion temperature between the critical extrusion temperature and the lower extrusion temperature limit cause changes in the proportions of beta soap, in the sudsing rate, and in the firmness of the resulting product. In general, for soap of any given composition, lower extrusion temperatures within these extremes result in a higher percentage of beta phase soap, and hence in a more rapidly soluble soap; lower extrusion temperatures also result in a softer product. In this respect soap made by my process differs greatly from soap made by the milling and plodding process, for milled soap that has been passed many times through milling rolls and as a result has a very high beta soap content is firmer than less thoroughly milled soap having a somewhat lower beta soap content.

In making a floating bar soap I prefer to employ extrusion temperatures below those at which the vesiculated air has a tendency to break through the surface of the soap after extrusion, causing an undesirably rough surface.

The amount of transformation to beta phase which occurs in my process under any given set of conditions with a soap of a given real soap formula may in general be increased (up to the maximum attainable under existing conditions for the particular soap being processed) by any of the following changes in conditions within the limits disclosed: lowering the extrusion temperature; lowering the moisture content of the soap supplied to the cooling device; increasing the amount of agitation per pound of soap produced; lowering the temperature of or increasing the rate of supply of the cooling medium. Thus the

beta content of soap produced by this process and the characteristics of the product which depend upon its beta content may be controlled as desired.

5 The amount of superatmospheric pressure to which the soap is subjected in cooling and agitating device 24 is not critical, the chief requirement being to supply sufficient pressure to force the soap into and through this device at the desired through-put rate. The pressure required to do this varies with the design and operation of the device and the nature of the soap.

10 The injection of air or other compatible gas into soap in my process and its fine dispersion as vesiculated gas throughout the solidifying soap mass does not interfere with or modify the phase changes which occur. The effects of this finely divided and well distributed air on the product are merely to make it somewhat lighter in color, more opaque, and somewhat softer than it would otherwise be, and to lower its density. The amount of air incorporated may be either more or less than the amount required to produce a density equal to that of water, and thus an aerated soap may be made either floating or non-floating as desired. The phase composition and related characteristics, such as free lathering quality, are not affected to a significant degree by aeration of the soap.

15 20 25 30 35 30 A suitable amount of air or other gas to introduce into the soap before it enters the cooling apparatus to produce a floating soap is that amount which will produce a warm extruded bar (at cutter 27) containing about 22 per cent of air by volume, which is equivalent to about 14 per cent by volume when the soap is cooled to room temperature and stamped or pressed into final bar shape.

35 40 45 50 If an aerated but non-floating product is desired, sufficient air to produce a bar at cutter 27 containing about 4 per cent or less of air or other gas may be incorporated. This is a sufficient amount to lighten the color of the product appreciably.

45 50 Perfume, preservative, coloring matter, or the like may if desired be incorporated in soap made by my process. When using the apparatus illustrated, any of these materials may be introduced into the soap in the continuous crutcher represented at 46 in Figure 1.

55 60 65 70 75 I find that, generally speaking, my process is applicable to, and that my product may be produced from, soap of any composition suitable for toilet, household, and laundry purposes, which has a real soap formula containing at least about 15 per cent of sodium soaps of saturated fatty acids having at least 16 and not more than 22 carbon atoms per molecule. I find that sodium soaps of lauric acid and of other saturated fatty acids having a smaller number of carbon atoms than lauric acid, and sodium soaps of oleic acid and of other unsaturated fatty acids which are liquid at ordinary temperatures, when treated by themselves are not transformed into the beta phase under the conditions described herein, although mixtures of soaps of these fatty acids with sodium soaps of saturated fatty acids containing from 16 to 22 carbon atoms per molecule may, if the mixture contains at least 15 per cent of such saturated sodium soaps, readily be transformed to the beta phase.

75 Sodium soaps made from different proportions of coconut oil and tallow, or from other fats or fatty acids, may be subjected to my process to produce soap of improved sudsing rate. In place

of coconut oil other tropical nut oils having similar characteristics may be substituted, and in place of tallow other fats and hydrogenated oils having similar soap making characteristics may be substituted. Soap making fats having characteristics different from those of tallow and coconut oil may also be used; likewise, water-soluble soaps of basic materials other than sodium may be substituted in part for sodium soaps. By analogy with the operating conditions described for the examples already given, those skilled in the art will readily recognize suitable operating conditions for any given formula.

In making substantially unbuilt soaps, that is soaps containing no more than about one per cent of soap builders, I find that with real soap formulas commonly used in making bar soaps for toilet and general household use the moisture content of the product is preferably no higher than about 27 per cent because such soap which contains over 27 per cent moisture tends to be so soft when extruded at preferred temperatures that it is difficult to handle without marring the bar surface. By employing sodium soaps of fatty acids of high titer I have, however, produced satisfactory bars having an improved sudsing rate with moisture contents as high as 32 per cent. I prefer a moisture content at least as high as ten per cent, because soap containing less than ten per cent moisture tends to be difficult to process because of its relative stiffness. When the moisture content of the soap is within the range ten per cent to thirty-two per cent but is close to either of these extremes, some adjustment in the composition of the real soap formula may be desirable to offset the resulting firmness or softness of the product.

My process is not limited to substantially "unbuilt" soaps such as are commonly employed for use in toilet and bath. It may be applied to soaps containing substantial amounts of builders, such as are suitable in soaps for general household and laundry use in the form of bars, flakes, or granules. For example, I have produced a bar soap having improved sudsing rate and containing a substantially increased beta soap content, by subjecting to my process a soap made by thoroughly mixing 75 parts by weight of kettle soap (made by saponifying a mixture consisting of 20 per cent coconut oil and 80 per cent tallow with 45 caustic soda solution) with 24 parts of an aqueous sodium silicate solution (having a density of 40.8° Bé. at 60° F., and having a ratio of SiO₂/Na₂O of 3.20) and 1 part of aqueous sodium hydroxide solution (having a density of 34.0° Bé. at 60° F.), and flash drying this mixture to a moisture content of 33 per cent. This soap was extruded from the cooling and agitating device at a temperature of 140° F. Likewise my process has been employed to increase the solution rates of laundry soaps containing soda ash and trisodium phosphate as builders. Other well known soap builders such as sodium perborate, sodium metasilicate, and sodium pyrophosphate may be employed. Inasmuch as the ordinary milling and plodding process is not applicable to soaps containing substantial amounts of alkaline builders my process is the first one known, so far as I am aware, for increasing the beta soap content of such soap products.

The grains or crystals of which my new soap is composed are apparently aligned or oriented substantially in one direction. This is a property which is also possessed by milled soaps but not by framed soaps or by soaps extruded at 75

such high temperatures that they are not form-retaining. The orientation of grains is in the direction of extrusion, and it imparts to the side surfaces of extruded bars (which are the surfaces that are normally rubbed during use) a solution rate about 10 per cent greater than that possessed by the end surfaces which are substantially perpendicular to the direction of extrusion. The orientation or lack of orientation of the particles of a soap can be demonstrated by observing a thin section of the soap (the broad surfaces of which are substantially parallel with the direction of extrusion) placed between crossed Nicol prisms, first with the section of soap turned to the position of maximum light extinction, and then with the section of soap turned 45° from its previous position. An increase in the amount of light transmitted as a result of turning the soap 45° from its position of maximum extinction is an indication of orientation of the particles of the specimen.

The processing steps of the usual milling and plodding operation appear to compact groups of minute soap grains into larger units which tend to be optically homogeneous, resulting in increased translucency. Extrusion of soap at low pressure as in my process, for example below about 510 pounds per square inch, does not appreciably compact the grains in this manner but does tend to orient the grains as previously mentioned. When examined microscopically with polarized light, samples of my new soap are found to contain optically homogeneous grains substantially all of which are less than 0.1 millimeter in average diameter, whereas samples of ordinary milled soap are found to contain predominantly much larger optically homogeneous grains averaging more than 0.2 millimeter in average diameter.

Mention has previously been made of the fact that my improved soap in its preferred form is more opaque than milled soaps. It is well known that milled soap is relatively translucent and as a result it is customary when making white milled soaps to incorporate a small quantity of a finely divided solid whitening or opacifying agent to render it opaque and thus improve its appearance. The relative opacity of soap may conveniently be measured by cutting a thin section or film of a representative sample of the soap, this film having a thickness of $\frac{1}{16}$ inch, and determining by means of a reflectometer the amount of light reflected under standardized lighting conditions, first when the film is placed on a perfectly black background, and second when the film is placed on a white background. The first reading multiplied by 100 and divided by the second reading I call the opacity value of the soap. This testing procedure is similar to that employed in determining the opacity of paper, as described in Sutermeister's "Chemistry of Pulp and Paper Making," 2nd edition, p. 479. I have found that a typical sample of soap made by my new method as herein described, except that the step of injecting gas was omitted, has an opacity value of 89, when measured on a surface that is substantially parallel with the direction of extrusion of the soap. Soap of the same real soap formula and the same moisture content when made by the milled soap process, except that no opacifying agent was added, this milled soap having substantially the same beta soap content as the aforementioned typical sample of my new soap as shown by their X-ray diffraction patterns, is found to have an opacity

value of only 70. Unaerated framed soap of the same real soap formula and the same moisture content is found to have an opacity value of 84.

Under comparable conditions as to bar size, bar temperature, age of bars, etc., my improved soap in its preferred form is found to be softer than ordinary milled soap of the same real soap formula, the extent of the difference in firmness between the two types of soap depending upon the moisture content and the extrusion temperature of my soap.

The superior sudsing ability of my novel product is due in some measure to its granular structure, in which term are included such characteristics as grain size, orientation of grains, relative firmness of the cohesion of grains, and softness of product for a given chemical and phase composition.

The terms "ordinary framed soap," "ordinary framed kettle soap," and "corresponding framed soap" designate soap made by cooling fluid soap from a temperature at which it will readily flow into the "frame," without producing undesirable streaks in the product due to viscous flow, to a temperature at which it is substantially solid, at a rate substantially that of the rate of cooling of the center portion of an ordinary "frame," containing about 1000 pounds of soap, cooled by natural convection of air having an initial temperature of about 85° F. Soap such as that sold for many years past under the trade-mark "Ivory" may be considered as a typical framed kettle soap of the floating variety.

Having thus described the invention, what is claimed as new and desired to be secured by Letters Patent is:

1. In a process of manufacturing detergent soap containing a substantial amount of soap in the beta phase, the steps which comprise chilling a soap mass, and while chilling said mass, effectively agitating the same and extruding the mass in continuous bar form, said agitating and extrusion being concluded while the soap mass is at a temperature at which the soap is in a condition of pasty cohesiveness, and is within the temperature range in which the beta phase as shown by X-ray diffraction photograph is formed in substantial amount upon agitating, whereby the sudsing rate of the soap is materially increased.

2. In the process of manufacturing detergent soap containing a substantial amount of soap in the beta phase, the steps which comprise effectively agitating an aerated soap mass and extruding said mass in continuous bar form while above a temperature at which the soap mass loses its pasty cohesiveness, and within the temperature which the beta phase as shown by X-ray diffraction photograph is formed in substantial amount upon agitating, whereby the sudsing rate of the soap is materially increased, and promptly chilling the extruded bar to an extent sufficient to stabilize the phase composition of the soap.

3. In a process of manufacturing detergent soap containing a substantial amount of soap in the beta phase, the steps which comprise flash drying to a moisture content of not less than about ten per cent molten neat soap of high temperature, chilling the soap and concurrently and effectively agitating the same and mixing all portions of the mass and extruding the same in continuous bar form, said agitating and extrusion being concluded while the soap mass is at a temperature at which the soap is in a condition of pasty cohesiveness, and is within the tempe-

ture range in which the beta phase as shown by X-ray diffraction photograph is formed in substantial amount upon agitating, whereby the sudsing rate of the soap is materially increased.

4. In a process of manufacturing detergent soap containing a substantial amount of soap in the beta phase, the steps which comprise flash drying to a moisture content of not less than about ten per cent molten neat soap of high temperature, chilling the resulting soap mass, chilling and concurrently and effectively agitating said mass and mixing all portions of the mass and extruding the mass in continuous bar form, said agitating and extrusion being concluded while the soap mass is at a temperature at which the soap is in a condition of pasty cohesiveness, and is within the temperature range in which the beta phase as shown by X-ray diffraction photograph is formed in substantial amount upon agitating, whereby the sudsing rate of the soap is materially increased.

5. In a process for preparing soap, containing a substantial amount of soap in the beta phase, and of formula suitable for toilet, household, or laundry use, the steps which include effectively agitating a mass of said soap while cooling said soap mass from a temperature at which same is molten to a temperature such that the mass is in a condition of pasty cohesiveness, and such that at least a substantial proportion of said mass is within the temperature range in which soap may by agitating action be transformed into the beta phase, the extent of agitation being sufficient to produce a soap product containing a substantial amount of soap in the beta phase, subjecting said agitated soap for a controlled period of time to an elevated temperature at which reversion from beta phase to omega phase occurs at a moderate rate, thereby controlling the sudsing rate of the finished product, and thenceforth subjecting said soap to temperatures at which soap in the beta phase is stable.

6. In a process for making floating bar soap, containing a substantial amount of soap in the beta phase, and of formula suitable for toilet and household use, the steps which include incorporating in and distributing throughout a mass of said soap a sufficient volume of a compatible gas to impart to the bar soap product a density less than that of water, effectively agitating said mass, while establishing and maintaining the same at temperatures such that the mass is in a condition of pasty cohesiveness, and such that at least a substantial proportion of said mass is within the temperature range in which soap may by agitating action be transformed into the beta phase, the extent of agitation being sufficient to produce a soap product containing a substantial amount of soap in the beta phase, and thenceforth subjecting said soap to temperatures at which the soap of beta phase contained therein is stable.

7. A process for preparing a floating bar soap of reduced moisture content and increased sudsing rate as compared with ordinary commercial floating framed kettle soaps and containing a substantial amount of soap in the beta phase, which comprises the steps of incorporating and uniformly distributing in minute bubble form a compatible gas throughout a continuous mass of molten soap containing from about 14 per cent to about 27 per cent moisture, the real soap formula of which contains at least about 15 per cent of sodium soaps of saturated fatty acids containing not less than 16 nor more than 22

carbon atoms per molecule, the proportion of said gas being sufficient to cause the finished product to float in water, cooling said soap mass to a temperature between about 160° F. and about 125° F., within which range beta phase soap as formed on agitation and at which same is in a condition of pasty cohesiveness, effectively agitating said soap while establishing and maintaining the same within said temperature range to transform a substantial portion of the soap to the beta phase, forming the resulting product into bars, and thenceforth subjecting said bars to temperatures below those at which reversion of beta phase to omega phase takes place.

8. A continuous process for preparing a floating bar soap, containing a substantial amount of soap in the beta phase, and suitable for toilet and household use, this soap being characterized by its increased sudsing rate as compared with floating framed soap of like formula and moisture content, which comprises the steps of: continuously incorporating compatible gas, in amount sufficient to impart buoyancy in water to the finished soap product, into a flowing mass of soap containing from about 14 per cent to about 27 per cent moisture and having a real soap formula including at least 15 per cent of sodium soaps of saturated fatty acids having not less than 16 nor more than 22 carbon atoms per molecule; continuously cooling said flowing mass from a molten condition above about 160° F. to a form-retaining condition of pasty cohesiveness between about 160° F. and about 125° F., within which range beta phase soap is formed on agitation; effectively agitating said mass both during said cooling step and immediately subsequent thereto in a manner adapted to transform a substantial portion of said soap to a more rapidly soluble form; extruding said cooled and agitated mass in uninterrupted blank bar form; and cutting said uninterrupted bar into individual bars.

9. A process for preparing a new type of floating bar soap, containing a substantial amount of soap in the beta phase, and suitable for toilet and household use, characterized by an increased sudsing rate as compared with ordinary commercial floating framed kettle soaps, which comprises the steps of continuously passing into a confined space molten soap, throughout which has been distributed in small bubble form a compatible gas in amount sufficient to impart buoyancy in water to the finished soap product, said soap containing from about 10 per cent to about 32 per cent moisture and having a real soap formula which contains at least about 15 per cent of sodium soaps of saturated fatty acids having not less than 16 nor more than 22 carbon atoms per molecule, continuously advancing said soap through said confined space and simultaneously cooling same in thin films from said molten condition to an average temperature between about 160° F. and about 125° F., within which range beta phase soap is formed on agitation, effectively agitating said soap both during said cooling step and immediately subsequent thereto while in said confined space to form a well mixed soap magma containing vesiculated gas distributed therethrough and to transform a substantial portion of said soap to a more rapidly soluble form, continuously extruding said soap from said confined space in blank bar form while in a condition of pasty cohesiveness, and thenceforth subjecting said extruded bar soap to temperatures below those at 75

which reversion of the more rapidly soluble form to the less rapidly soluble form occurs.

10. A process for preparing floating bar soap, containing a substantial amount of soap in the beta phase, and suitable for toilet and household use which comprises the steps of: continuously passing molten soap into a confined space, said soap containing about 20 per cent to 27 per cent moisture, said soap having a real soap formula consisting of about 75 per cent to 85 per cent sodium soaps of fatty acids of the tallow type and about 25 per cent to 15 per cent sodium soaps of fatty acids of the coconut oil type, and said soap having incorporated and distributed throughout same an amount of air sufficient to reduce the specific gravity of the soap to about 0.75 to 0.85, measured soon after extrusion from said confined space; continuously advancing said soap through said confined space and simultaneously cooling same from said molten condition to a partially solidified condition at a temperature between about 160° F. and 140° F., within which range beta phase soap is formed on agitation; effectively agitating said soap both during said cooling step and immediately subsequent thereto while in said confined space; and continuously extruding said soap from said confined space in blank bar form.

11. A detergent bar soap having a real soap formula containing at least about 15 per cent of sodium soaps of saturated fatty acids having not less than 16 nor more than 22 carbon atoms per molecule, and having the granular structure and phase composition characteristic of a soap which has been effectively agitated and extruded while above a temperature at which the soap loses its pasty cohesiveness, and within the temperature range in which the beta phase as shown by X-ray diffraction photograph is formed in substantial amount upon agitating, and which has cooled substantially to room temperature without further agitation, said bar soap containing a substantial proportion of soap in the beta phase uniformly distributed therethrough.

12. A detergent soap containing a substantial amount of soap in the beta phase and having a real soap formula containing at least about 15 per cent of sodium soaps of saturated fatty acids having not less than 16 nor more than 22 carbon atoms per molecule, having a phase composition of the character that results from effectively agitating a mass of said soap while cooling same from a molten condition to a form-retaining condition of pasty cohesiveness below its critical temperature, and having a granular structure of the character that results from extruding said cooled agitated mass at a pressure insufficient to compact the grains thereof into substantially larger optically homogeneous units.

13. In a process of manufacturing detergent soap containing a substantial amount of soap in the beta phase, the steps which comprise effectively agitating a soap mass while said mass is within a temperature range in which the beta phase of said soap is formed in substantial amount upon agitating and while above that temperature below which said mass loses its pasty cohesiveness, and extruding said mass in continuous bar form while within said temperature range and while above that temperature below which said mass loses its pasty cohesiveness.

14. In a process of manufacturing detergent soap containing a substantial amount of soap in the beta phase, the steps which comprise effec-

tively agitating an aerated soap mass while said mass is within a temperature range in which the beta phase of said soap is formed in substantial amount upon agitating and while above that temperature below which said mass loses its pasty cohesiveness, and extruding said mass in continuous bar form while within said temperature range and while above that temperature below which said mass loses its pasty cohesiveness.

15. A detergent bar soap having a real soap formula containing at least about 15 per cent of sodium soaps of saturated fatty acids having not less than 16 nor more than 22 carbon atoms per molecule, and having the granular structure and phase composition characteristic of a soap which has been effectively agitated and extruded while above a temperature at which the soap loses its pasty cohesiveness, and within the temperature range in which the beta phase as shown by X-ray diffraction photograph is formed in substantial amount upon agitating, and which has cooled substantially to room temperature without further agitation, said bar soap containing a substantial proportion of soap in the beta phase uniformly distributed therethrough and containing a compatible gas substantially uniformly distributed therethrough in minute vesicular form.

16. A soap of formula suitable for toilet, household and laundry use, containing a substantial proportion of sodium soap in the beta phase, and having the granular structure typical of a soap which has been whipped mechanically while at a temperature such that the mass is in a condition of pasty cohesiveness and while within the range in which beta soap is formed on agitation, and which has been maintained, both during said whipping and thereafter until fully solidified, at pressures sufficiently low to avoid substantial compacting of soap grains such as would substantially increase the translucency and firmness of said soap.

17. A floating bar soap suitable for toilet and household use containing a fine dispersion of vesicles of a compatible gas in sufficient quantity to reduce the density of said soap below that of water, said soap containing from about ten per cent to about twenty-seven per cent of moisture, having a real soap formula including at least fifteen per cent of sodium soaps of saturated fatty acids having not less than sixteen nor more than twenty-two carbon atoms per molecule, containing a substantial proportion of sodium soap in the beta phase, and having the granular structure typical of a soap of said composition which has been cooled from a molten condition above about 160° F. to a form-retaining condition of pasty cohesiveness, in which condition said soap is a mixture of soap in solid phase and soap in non-solid phase, between about 160° F. and about 125° F., within which range beta phase soap is formed on agitation, and which while being so cooled and immediately subsequent thereto has been effectively agitated, and which has subsequently been extruded while still in 65 said condition of pasty cohesiveness.

18. A floating bar soap suitable for toilet and household use, containing a fine dispersion of vesicles of a compatible gas in sufficient quantity to reduce the density of said soap below that of water, said soap containing from about ten per cent to about twenty-seven per cent of moisture, having a real soap formula composed of about seventy per cent to ninety per cent sodium soaps of fatty acids of the tallow type and about thirty per cent to ten per cent sodium soaps of fatty acids of the coconut oil type, containing a substantial proportion of soaps in the beta phase, and having the granular structure typical of a soap of said composition which has been cooled from a molten condition above about 160° F. to a form-retaining condition of pasty cohesiveness, in which condition said soap is a mixture of soap in solid phase and soap in non-solid phase, between about 160° F. and about 125° F., within which range beta phase soap is formed on agitation, and which while being so cooled and immediately subsequent thereto has been effectively agitated, and which has subsequently been extruded while still in said condition of pasty cohesiveness.

19. A detergent bar soap having a real soap formula containing at least about 15 per cent of sodium soaps of saturated fatty acids having not less than 16 nor more than 22 carbon atoms per molecule, and having the granular structure and phase composition characteristic of a soap which has been effectively agitated and extruded while above a temperature at which the soap loses its pasty cohesiveness, and within the temperature range in which the beta phase as shown by X-ray diffraction photograph is formed in substantial amount upon agitating, and which has cooled substantially to room temperature without further agitation, said bar soap containing a substantial proportion of soap in the beta phase uniformly distributed therethrough and containing a substantial amount of a soap builder.

20. A detergent bar soap having a real soap formula containing at least about 15 per cent of sodium soaps of saturated fatty acids having not less than 16 nor more than 22 carbon atoms per molecule, and having the granular structure and phase composition characteristic of a soap which has been effectively agitated and extruded while above a temperature at which the soap loses its pasty cohesiveness, and within the temperature range in which the beta phase as shown by X-ray diffraction photograph is formed in substantial amount upon agitating, and which has cooled substantially to room temperature without further agitation, said bar soap containing a substantial proportion of soap in the beta phase uniformly distributed therethrough, containing a substantial amount of a soap builder, and containing a compatible gas substantially uniformly distributed therethrough in minute vesicular form.

VICTOR MILLS.

CERTIFICATE OF CORRECTION.

Patent No. 2,295,594.

September 15, 1942.

VICTOR MILLS.

It is hereby certified that error appears in the printed specification of the above numbered patent requiring correction as follows: Page 1, second column, line 35, for "diagrammatic" read --diagrammatic--; line 51-52, for "intion" read --invention--; page 6, second column, line 28, for "510 pounds" read --50 pounds--; page 7, first column, line 58, claim 2, before "which" insert --range in--; and that the said Letters Patent should be read with this correction therein that the same may conform to the record of the case in the Patent Office.

Signed and sealed this 24th day of November, A. D. 1942.

Henry Van Arsdale,

Acting Commissioner of Patents.
